UNITED STATES PATENT OFFICE

WILLIAM TOWNLEY, DECEASED, LATE OF ACCRINGTON, ENGLAND, BY NANCY TOWNLEY, EXECUTRIX, OF ACCRINGTON, ENGLAND, ASSIGNOR TO ENTWISLE & KENYON LIMITED, OF ACCRINGTON, ENGLAND

CARPET SWEEPER

Application filed February 14, 1929, Serial No. 339,918, and in Great Britain August 23, 1928.

This invention relates to carpet sweepers and more particularly to improvements in the mechanism for operating the dust pans, of the type in which a spring wire attached to each dust pan is connected to one end of a pivoted lever to the other end of which is pivotally connected on arm passing through a slot in a finger plate on the casing of the 5 sweater so that by depressing this arm the dust pans are caused to open whilst on releasing the arm the spring wire causes them to close.

The object of the present invention is to provide means whereby the dust pans will 10 be held or locked in their open position when the arm passing through the sweater casing is depressed.

According to the invention a recess is formed near the top of the arm to provide a 15 shoulder so that when the arm has been depressed to open the dust pans it can be moved laterally and the shoulder will engage the finger plate and hold the dust pans in their open position until the arm is released by 20 moving it back from the end of the slot.

The invention will be described with reference to the accompanying drawings:—

Fig. 1 is a transverse section of a carpet 25 sweeper showing the invention applied thereto.

Fig. 2 is a plan of part of a carpet sweeper showing the invention applied thereto.

Fig. 3 is a perspective view of a corner of a carpet sweeper showing one form of locking 35 device in the normal position.

Fig. 4 is a similar perspective view showing the locking device in the depressed position for holding the dust pans in the open position.

Fig. 5 is a perspective view of a corner of a carpet sweeper showing another form of locking device in the normal position.

Fig. 6 is a similar perspective view showing the locking device in the depressed position for holding the dust pans in the open position.

Fig. 7 is a plan view of the finger plate.

Fig. 8 is a section through the finger plate and locking arm.

Each dust pan A is connected by a spring

wire *a* to one end of a pivoted lever B, to the other end of which an arm C is pivotally connected. The arm C passes through a slot *d* in a finger plate D on the casing of the 55 sweater so that by the depression of the arm C the dust pans A are caused to open whilst on releasing the arm C the spring wire *a* causes them to close.

The above described arrangement for operating the dust pans is of known construction and while it operates the dust pans successfully it has no means for holding or locking 60 the dust pans in the open position.

In the form of the invention shown in Figs. 3 and 4 a recess is formed near the top of the 65 arm C to provide a shoulder *c* at its top end so that when the arm has been depressed to open the dust pans A it can be moved laterally to allow the shoulder *c* to engage under the finger plate D at the end of the slot *d* to hold the dust pans A in their open position until the arm is released by moving it 70 back from the end of the slot *d*.

In the form of the invention shown in Figs. 5 to 8 means are also provided to prevent 75 the arm C¹ which is L shaped in cross section being moved laterally until it has been depressed. In this construction the slot in the finger plate D¹ is made L shaped with two branches *d*², *d*¹ through one of which *d*² 80 the arm C¹ projects this slot *d*² being made longer than the width of the arm C¹ so that the latter can move laterally therein. A flange *c*¹ is formed along one edge of the arm C¹ and passes through the second slot 85 *d*¹ at right angles to the slot *d*². A recess is formed in the flange *c*¹ to provide a shoulder *c*² at its top end so that when and not until the arm C¹ has been depressed to its full extent the flange *c*¹ will be clear of the second slot *d*¹ and the arm C¹ can be moved laterally to bring the edge of the shoulder *c*² below the edge of the finger plate D¹ to hold the dust pans A in the open position.

What is claimed is:—

In mechanism of the type referred to for holding the dust pans of a carpet sweeper open, the combination with a finger plate provided with an L-shaped slot, an operating arm L-shaped in cross section extending 100

through said slot and operatively connected with said pans, said arm being provided with a shoulder at its top and to engage under said plate when said arm is depressed.

5 In testimony whereof I have hereunto set my hand this 31st day of January, 1929.

NANCY TOWNLEY,
Executrix of William Townley, Deceased.
